Baldwin & Wright.*

UNITED STATES PATENT OFFICE.

EDWARD B. HESS, OF MANHATTAN BEACH, NEW YORK, ASSIGNOR TO ROYAL TYPE-WRITER COMPANY, INC., OF NEW YORK, N. Y., A CORPORATION OF NEW YORK.

TYPEWRITING MACHINE.

Application filed November 2, 1921. Serial No. 512,352.

To all whom it may concern:

Be it known that I, EDWARD B. HESS, a citizen of the United States, residing at Manhattan Beach, in the county of Kings, 5 New York, and State of New York, have invented certain new and useful Improvements in Typewriting Machines, of which the following is a specification.

This invention relates to front strike 10 visible typewriting machines, in which the type bar segment is raised and lowered for case printing while the platen is held against vertical movement but is free to move crosswise of the machine in the usual 15 way.

My present invention involves novel 20 mechanism for operating the type bars for raising and lowering the type bar segment and for operating the escapement.

The mechanism for operating the type 25 bars is so constructed that the type bars, instead of being moved by the keys from a position of rest to the printing point, are moved to a predetermined position considerably in advance of the platen, being carried to the printing point by their momentum. In this way, the noise of the impact 30 of the type on the platen is materially reduced.

In my United States Patent No. 1,390,708 35 of Sept. 13, 1921, I have shown a type bar action so constructed as to reduce noise, the type action being movable by the full depression of a key to such an extent as to move the associated type bar to a predetermined position in front of the platen and at such distance therefrom as to reduce noise during a further movement of the type bar 40 about its pivot to the platen caused by the momentum of the type bar.

My present invention involves the adaptation of the mechanism of said patent to a machine in which the type bar segment is shifted for case printing instead of the platen being raised and lowered for this 45 purpose.

In carrying out my invention in the preferred way, the type bar segment is supported by springs adapted to hold it at lower case position. The springs encircle 50 vertical rods or posts which are suitably guided in the machine frame and stops are employed to limit the movement of the segment in both directions.

The shift key has an upwardly extending 55 arm, which is link connected to an arm on a horizontally arranged shaft, which is provided with arms that have slot and pin connections with the segment supporting rods. When the shift key is depressed to its full 60 extent, the segment is lowered and it may be held in the lower position by a shift key locking device provided with a finger piece, by means of which the lock may be opened 65 to allow the segment to rise to normal position.

The type bars are pivoted at their inner 70 or rear ends to the segment while their front ends are normally supported by a cushioned type bar rest connected by frame pieces to the segment so as to rise and fall therewith. The type bars are connected with the key levers by a system of links and levers arranged in a novel way and in such manner that some of the parts are moved 75 to a toggle locking or dead center position when the keys are fully depressed, a further movement of the type bars to the print point being caused by the momentum of the type bars. In this way noise is reduced. The 80 type bar action just described is so organized that it operates efficiently and in the same way in either position of the type bar seg- 85 ment.

The carriage escapement is operated by 90 parts of the type bar action, the release taking place during the momentum period of the type bars, i. e., when they are passing from their dead center or toggle locking position to the printing point. Preferably 95 the connections between the key levers and the type bars comprise horizontally arranged levers which are link connected with the key levers and are link connected with two-armed levers carried by a stationary segment in rear of the type bar segment. These two-armed levers are link connected with the type bars above and in front of their pivots.

In the accompanying drawings:—

Figure 1 is a view partly in section and 100 partly in side elevation of parts of a type-writing machine with my improvements applied, only such parts of the mechanism being shown as are necessary to illustrate 105 my improvements.

Figure 2 is a diagrammatic view showing the connections of a type bar with certain

levers in the type bar action and this figure illustrates by full lines the dead center or toggle locking position and also by dotted lines the position of these parts after the dead center position has been passed.

A portion of a typewriter carriage is indicated at A, and B indicates a platen. C indicates the escapement mechanism and D the type bar segment. A type bar guide 10 E is attached to the segment and is raised and lowered therewith. The segment is as usual semi-circular and the type bars F are pivotally connected therewith at f, while the outer ends of the type bars are normally 15 supported in a cushioned type bar rest G connected by frame pieces G' with the segment D in such manner that the type bar rest moves up and down with the segment. The segment D is supported by springs H encircling posts or rods I which are attached to the under side of the segment and extend through the laterally projecting portions j of a frame or bracket J. The springs H rest on nuts K which engage tapped openings in the extinctions j. The rods I extend through the extinctions j and also through nuts L below the extension. By adjusting the nuts K, the tension of the spring H may be adjusted. Each rod I also extends 20 through a part j' of the frame or bracket J and through a nut M which has a threaded connection with the bracket. Each rod I carries a collar N which is fastened as indicated at n to the rod. By adjusting 25 the nuts L and M, the vertical movement of the rods and consequently of the segment may be adjusted. The rods I have a slot and pin connection indicated at O with arms P extending from a horizontally arranged 30 shaft Q from which extends an arm q connected by a link R with the arm S of the shift key lever S'. The drawings show only one shift key as being connected with the shaft Q, but it is understood that if another 35 such key is employed, it is similar in construction to that shown and is connected with the shaft Q in a similar way. The type bar segment normally occupies a raised position for lower case printing. When 40 a shift key is depressed, the segment is lowered for upper case printing and may be held in such position by the finger of the operator or may be automatically held in upper case position by means of the shift 45 lock devices T, comprising a lever t pivoted at t' to the shift key S' and connected by a spring t² to a lug t³ on the lower part of the lever S'. The lever S' carries a stop s against which the lever t is pulled by the spring t², and the lever t is notched at t⁴ near its upper end, adapting it to engage an adjustable pin t⁵ on the frame of the machine. When the shift key S' is depressed, the lever t automatically engages the pin t⁵ and holds the shift key in

lowered position or in such position as to hold the type bar segment in lower position. By merely pressing down on the lever t, it may be disengaged from the pin t⁵ and the shift key will rise to normal position. The 70 shift key is pivotally mounted in the frame U on a rod U', and the key levers V for operating the type bars are also pivotally mounted on said rod. The key levers are held normally in raised position against a stop A' by springs W attached to a frame w placed adjacent a frame X in which are mounted a series of horizontally arranged levers Y which are connected by links y with the key levers V. These levers Y extend rearwardly from the frame X to the rear part of the machine and are connected by links Y' with two-armed levers Z which are pivotally mounted in a stationary segment Z' arranged in rear of the movable segment D. 75 It will be understood that there is one such two-armed lever Z for each key lever and each type bar. The type bars F, as before stated, are pivotally mounted in the movable segment D. They are held in normal position and prevented from vibrating by springs f' attached to lugs f² extending from the lower portions of the type bars to a frame F'. Each type bar has an upwardly 80 extending lug f³ which is connected by a link d with a two-armed lever Z. The connections are such that when a key lever V is depressed, the corresponding lever Y is moved downward and operates upon the two-armed lever Z by the link connections shown, to raise a type bar to the inclined dotted line position shown in Figure 1, at F^x such position being considerably more than five degrees from the platen and at such distance therefrom as to reduce noise during 85 a further movement of the type bar to the platen caused by its momentum. The connections are also such that when a key lever is depressed to its full extent, parts of the action are brought to a toggle locking or dead center position. This is illustrated in 90 Figure 2. As there shown, the center about which the lever Z moves is indicated at z. The link Y' has a pivotal connection at z' with the lever Z and it has a pivotal connection at y with the lever Y. Figure 2 shows by full lines that the parts z, z' and y are in a straight line which is a toggle locking or dead center position, the parts 95 being brought to this position by a full depression of a key lever. The momentum of the type bar, however, carries the parts to the dotted line position, Figure 2, thus moving the parts out of the dead center position and during this movement the type bar is carried to the printing point. 100

The organization is such that in the upper or lower position of the type bar segment, the type bars are operated in the same way, i. e., 105 they are moved by the full depression of the 110

key levers to a point considerably in advance of the platen, the further movement of the type bars to the printing point being caused by their momentum.

- 5 The escapement mechanism shown comprises a frame C' carried by hangers c pivotally connected with the machine frame at c' and pivotally connected at c¹⁰ with the frame C'. The front portion of the frame C' has
 10 a downwardly extending arm having a rearward extension c² which is adapted to make contact with the escapement rocker C². A spring c¹¹ tends to draw the upper end of the rocker rearwards, and a spring c⁷ tends
 15 to draw the frame C' forward, the forward movement of the frame C' being limited by a screw c⁵ which engages a lug c⁴ on one of the hangers c. The screw c⁶ limits the rearward movement of the upper end of the rocker.

Normally the levers Z occupy the position shown by full lines in Figure 1, the upper front portion of the levers Z being disposed a considerable distance in advance of the frame C'. When a key lever is depressed to its full extent, it moves the associated two-armed lever Z to the dotted line position shown at z, Fig. 1, and brings the upper end of the lever into contact with the frame C' without moving it. When the type bar by its momentum moves from its position F* to the printing point, the lever Z moves to the position shown by dot and dash lines y and in doing so moves the frame C' rearwards and operates the escapement. The frame C' is in fact a universal bar. It is semi-circular in shape and is engaged by all the levers Z. It will thus be seen that in the preferred construction the universal bar which operates the escapement mechanism is actuated during the latter part of the movement of the type bars and, in fact, during the momentum period thereof. In this way the operation of the escapement is greatly improved.

While as before stated, one part of my invention consists in adapting the type bar action of my patent of Sept. 13, 1921 to a typewriting machine in which the type segment is raised and lowered for case printing, my invention also involves certain novel features of construction which may be used without necessarily using the type bar action specified.

55 Preferably the lower case letters are placed on the inner or lower ends of the heads of the type bars and therefore print when the type bar segment is in its normal or raised position. The segment is lowered for upper case printing to properly bring the upper case letters to the printing point on the platen.

I claim as my invention:

- 60 1. In a typewriting machine, the combination with the key levers and the type bars,

of a vertically movable segment to which the type bars are pivoted, posts depending from the segment, brackets through which the posts extend, springs surrounding the posts for normally holding the segment in its upper position, nuts engaging the brackets for adjusting the tension of the springs and means for depressing the segment to its lower position.

70

2. In a typewriting machine the combination with the key levers and the type bars, of a vertically movable segment to which the type bars are pivoted, posts depending from the segment, springs surrounding the posts for normally holding the segment in upper position, brackets through which the posts extend, collars carried by the posts and adjustable nuts through which the posts extend and which are adapted to engage the collars to limit the movement of the posts.

75

3. In a typewriting machine the combination with the key levers and the type bars, of a vertically movable segment to which the type bars are pivoted, means for normally holding the segment in its upper position, a shift key having an upwardly projecting arm at its rear end, a rock shaft to which said arm is link connected and connections between said rock shaft and the segment for moving it to its lower position.

80

4. In a typewriting machine the combination with the key levers and the type bars, of a vertically movable segment to which the type bars are pivoted, posts depending from the segment, springs surrounding the posts for normally holding the segment in its upper position, a shift key, a rock shaft to which it is link connected, and arms on the rock shaft operatively connected with the segment posts.

95

5. In a typewriting machine the combination with the key levers and the type bars, of a vertically movable segment to which the type bars are pivoted, and a noise reducing type action comprising connections between a type bar and a key lever movable to such an extent by the full depression of the key in either position of the segment as to move the type bar to a predetermined position in front of the platen and at such a distance therefrom as to reduce noise during a further movement of the type bar about its pivot to the platen caused by the momentum of the type bar.

110

6. In a typewriting machine the combination with the key levers and the type bars, of a vertically movable segment to which the type bars are pivoted, and a noise reducing type action comprising toggle-link connections between a type bar and a key lever movable to such an extent by the full depression of a key in either position of the segment as to move the associated type bar to a toggle-locking position in front of the platen and at such distance therefrom as

115

120

125

130

to reduce noise during the further movement of the type bar about its pivot to the platen caused by the momentum of the type bar.

7. In a typewriting machine the combination with the key levers and the type bars, of a vertically movable segment to which the type bars are pivoted, and a noise reducing type action comprising connections between a type bar and an associated key lever movable to such an extent by the full depression of an associated key in either position of the segment as to move the associated type bar to a position in front of the platen and at a distance therefrom considerably more than 5° and at such distance as to reduce noise during a further movement of the type bar about its pivot to the platen caused by the momentum of the type bar.

8. In a typewriting machine the combination with the key levers and the type bars, of a vertically movable segment to which the type bars are pivoted, a stationary segment in rear of the type bar segment, two armed levers mounted in said stationary segment, link connections between said levers and the type bars, levers intermediate the two armed levers and the key levers, and link connections between said intermediate levers and the key levers and between the intermediate levers and the two armed levers.

9. In a typewriting machine the combination of the key levers and the type bars, of a vertically movable segment to which the type bars are pivoted, a stationary segment in rear of the type bar segment, two armed levers pivotally mounted in said stationary segment, link connections between said two armed levers and the type bars in front of and above their pivots, intermediate levers between the two armed levers and the key levers and link connections between the key levers, the intermediate levers and the two armed levers.

10. In a typewriting machine the combination with the key levers and the type bars, of a vertically movable segment to which the type bars are pivoted, and con-

nections between the key levers and the type bars comprising two armed levers mounted in rear of the type bar pivots, intermediate levers between the two armed levers and the key levers, link connections between the two armed levers and the type bars and link connections between the intermediate levers and the two armed levers, said last mentioned links having pivotal connections at opposite ends with the intermediate levers and the two armed levers which are movable to such an extent by the full depression of the keys as to move said pivotal connections to a dead center position with the type bars at a considerable distance from the platen, the further movement of the type bars to the platen being caused by their momentum.

11. In a typewriting machine, the combination with the key levers and type bars, of a vertically shiftable segment in which the type bars are pivoted, non-shiftable levers mounted in the rear of the type bar pivots, operative connections between said levers and type bars, connections between the levers and the key levers including links which are movable to a dead center position by a full depression of the keys with the type bars at a distance from the platen from which position they complete their travel by momentum alone, thereby reducing noise.

12. In a typewriting machine, the combination with the key levers and type bars, of a vertically shiftable segment in which the type bars are pivoted, non-shiftable levers mounted in the rear of the type bar pivots, operative connections between the levers and the type bars, connections between the levers and the key levers including links the ends of which are movable into a straight line with the pivots of the non-shiftable levers by a full depression of the key levers with the type bars at a distance from the platen, from which position they complete their travel through momentum alone, thereby reducing noise.

In testimony whereof, I have hereunto subscribed my name.

EDWARD B. HESS.
